(57) CLAIM

The ornamental design for an electrical connector, as shown and described.

DESCRIPTION

FIG. 1 is a front elevation view of an electrical connector;

FIG. 2 is a rear elevation view thereof;

FIG. 3 is a top plan view thereof;

FIG. 4 is a bottom plan view thereof;

FIG. 5 is a right side elevation view thereof;

FIG. 6 is a cross sectional view of the connector taken along the line VI—VI of FIG. 1;

FIG. 7 is a perspective view of the front and right side thereof; and,

FIG. 8 is another perspective view showing a condition where the electrical connector is used.

A left side elevation view of the electrical connector is omitted, because it is presented symmetrical to the right side elevation view of FIG. 5.

The dashed lines in FIGS. 2 and 4 are included for the purpose of illustrating a portion of the connector that forms no part of the claimed design. The dashed line representation of a flexible printed circuit board or cable used with the electrical connector in FIG. 8 is included to illustrate environmental structure and forms no part of the claimed design.
